JOSIAH COPLEY, JR., OF ALLEGHENY CITY, PENNSYLVANIA, ASSIGNOR
TO JOSIAH COPLEY, SR., OF SAME PLACE.

Letters Patent No. 69,977, dated September 24, 1867; antedated August 17, 1867.

IMPROVEMENT IN BALANCED "HEAVE-UP" FOR ROLLING IRON.

The Schedule referred to in these Letters Patent and making part of the same.

TO ALL WHOM IT MAY CONCERN:

Be it known that I, JOSIAH COPLEY, Jr., of the city of Allegheny, in the county of Allegheny, and State of Pennsylvania, have invented a new and useful Improvement in Balance "Heave-Up" for Rolls, used for rolling iron; and I do hereby declare the following to be a full and exact description thereof, reference being had to the accompanying drawings, and to the letters and figures of reference marked thereon.

The nature of my invention consists in an improved balance "heave-up," constructed, arranged, and operating substantially as hereinafter described.

To enable others skilled in the art to make and use my invention, I will proceed to describe its construction and operation.

In the accompanying drawings, which form part of my specification—

Figure 1 is a side elevation of my improved balance "heave-up," representing it lowered; also representing a longitudinal section through the masonry surrounding said balance "heave-up."

Figure 2 is a side elevation of the same, representing the "heave-up" as raised.

Figure 3 is a top view of the same.

Figure 4 is a top view of the same, with the platforms and rolls removed.

In the drawings, A represents the masonry surrounding the balanced "heave-up," and B the pit for the same; C and C' the platforms on which the iron to be rolled is placed. These platforms may consist of frames and rollers, or any other device which may facilitate moving the iron. The platforms C and C' are supported by the frames D, which are pivoted to the levers f and arms e, said levers and arms being pivoted to the hausing J of the rolls x and x'. To the inner ends of the levers f is suspended the counterpoise h, by means of the links i. The pin n in the frame D, when said frame is depressed, is caught by the latch m, as represented in fig. 1.

The operation of my improvement is as follows: The "heave-up" being in the position represented in fig. 1, the iron is placed on one of the platforms, and passed between the rolls. The latch m is then unshipped, and the counterpoise having been sufficiently weighted, will heave up the platforms, thus raising the iron up so that it may be passed over the roll x' on to the other platform. The platforms are then lowered to their original position, by the operator pressing down on any part of either, since the descent of either platform raises the counterpoise so that the other platform descends by its own weight. When the "heave-up" is lowered, it is caught and held by the latch m. By making the outer arms of the levers of unequal lengths, the counterpoise will heave up the iron while on one platform, as before; but when it is on the other the iron will preponderate, and descend, thus making the "heave-up," in this respect, self-acting.

Having thus described the nature, construction, and operation of my improvement, what I claim as of my invention, is—

1. Combined with rolls for rolling iron, an improved balanced "heave-up," constructed and counterpoised substantially as herein described and for the purpose set forth.

2. The combination of the platforms C and C', frames D, levers f, arms e, and counterpoise h, with rolls for rolling iron, substantially as herein described and for the purpose set forth.

JOSIAH COPLEY, JR.
